[57] CLAIM

The ornamental design for a litter scoop, as shown and described.

DESCRIPTION

FIG. 1 is a top perspective view of a litter scoop showing my new design;

FIG. 2 is a top plan view thereof;

FIG. 3 is a front elevational view thereof;

FIG. 4 is a rear elevational view thereof;

FIG. 5 is a bottom plan view thereof; and

FIG. 6 is a right side elevational view thereof, the left side being a mirror image of the right side shown.

Fig. 2**Fig. 3****Fig. 4**
